(57) **CLAIM**

The ornamental design for an ambulatory protective device, as shown and described.

DESCRIPTION

FIG. 1 is a side elevational view of an ambulatory protective device showing my new design (the other side being the mirror image of FIG. 1);

FIG. 2 is a front elevational view of thereof;

FIG. 3 is a back elevational view thereof;

FIG. 4 is a top plan view thereof; and,

FIG. 5 is a bottom plan view thereof.

The broken lines in the drawings depict claimed stitching.
